UNITED STATES PATENT OFFICE.

JOHN MILAN, OF MISSOULA, MONTANA.

SLUICE-BOX.

SPECIFICATION forming part of Letters Patent No. 644,994, dated March 6, 1900.

Application filed July 20, 1899. Serial No. 724,530. (No model.)

To all whom it may concern:

Be it known that I, JOHN MILAN, a citizen of the United States, residing at Missoula, in the county of Missoula and State of Montana, 50 have invented a certain new and useful Sluice-Box, of which the following is a specification, reference being had therein to the accompanying drawings.

This invention relates to sluice-boxes, and 10 is especially adapted for concentrating magnetic black sand.

It is well known that certain magnetic black sand contains values of gold, lead, copper, platinum, &c.; and it is the object, as 15 indicated, of this invention to provide a convenient mechanism for concentrating such sand.

The invention consists in the combination of a main sluice-box provided with riffles, a 20 secondary or auxiliary sluice or spout also provided with riffles, pipes or passages leading from the base of the riffles in the main sluice-box to the auxiliary conduit, and means for intermittently cutting in and cutting out the auxiliary conduit.

The invention also consists in certain details of construction hereinafter described and claimed.

In the drawings, Figure 1 is a perspective 30 of my improved apparatus. Fig. 2 is a section on the line 2 2 of Fig. 1 looking in the direction indicated by the arrow in Fig. 1. Fig. 3 is an enlarged section of the spout or conduit constituting the auxiliary sluice.

1 is the main sluice, provided with riffles 35 2 of ordinary character. Leading from above the riffles or shoulders forming the riffles are series of pipes or passages 3 3, which discharge into the auxiliary sluice or spout 4. The spout 4 is also provided with riffles 5 and 40 with a cap 6. The pipes or passages leading from the main sluice 1 to the auxiliary sluice or spout 4 are preferably made in two parts, one of the parts being connected with the sluice 1 and the other being connected with the auxiliary spout 4. The pipes are formed 45 so as to telescope with each other, so that the auxiliary spout or sluice may be attached to

and detached from the main sluice. 7 is a tank or receptacle for receiving that part of 50 the concentrates which passes beyond the riffles 5 in the auxiliary sluice.

In order that the auxiliary spout or sluice may be cut into and out of connection with the main sluice, I provide a series of gates or 55 valves 8 8, arranged to swing laterally and upwardly from the openings in the side of the main sluice leading to pipes 3, and in order to operate all of these gates simultaneously I connect their upper ends with a bar 9 and 60 the bar with an operating-lever 10.

In operation the black sand or ore to be treated is fed to the main sluice in the usual way, the gates being closed. When the riffles have been filled or substantially filled 65 65 with concentrates, the feeding of the ore or sand is suspended, the gates are opened, and clean water is fed into the sluice, which carries the concentrates laterally through the passages 3 to the auxiliary spout 4, where the 70 free gold is collected behind the iron riffles in the auxiliary spout. The black sand containing gold in combination with other metals and the fine gold passes to the tank or receptacle 7, from which it is taken to the smelter 75 for further treatment. When the ore has all been carried from the main sluice, the water is cut off, the auxiliary sluice is removed from its connection with the main sluice, the cap removed, and the free gold caught on riffles 80 5 is discharged from the spout by turning the same to a vertical position.

Having described my invention, what I 85 claim as new, and desire to secure by Letters Patent, is—

1. An ore-concentrator involving the combination of a main sluice having riffles and having pipes or passages projecting laterally from one side of the sluice at the head of the riffles, an auxiliary sluice or spout having 90 iron riffles and pipes or passages adapted to telescope with the pipes projecting from the main sluice, and laterally and upwardly swinging gates or valves for opening and closing the passages, substantially as described. 95

2. In concentrating apparatus, the combination of a main sluice having riffles and having pipes or passages leading from one side at the head of the riffles, an auxiliary sluice or spout having pipe connections adapted to telescope with the pipe connections of the main sluice and having iron riffles, means for cutting in and cutting out the auxiliary spout,

and a cap for closing one end of the auxiliary spout, substantially as described. 10

In testimony whereof I affix my signature in presence of two witnesses.

JOHN MILAN.
